UNITED STATES PATENT OFFICE

JOSEPH A. LINDENFELSER, OF ROGERS, MINNESOTA

GRINDING BURR

Application filed March 25, 1929. Serial No. 349,546.

My invention relates to grinding burrs. This invention is in the nature of an improvement upon grinding burrs used in well known machines for grinding ear-corn so that both 5 the cobs and grain are reduced to meal at the same time. Grinding burrs of this general character are disclosed for example in Patent No. 1,587,863 issued June 8, 1926. An object of the present invention is to provide 10 a novel construction of burr and arrangement of teeth and ribs thereon which shall be eminently efficient for reducing both the cobs and the grain or kernels to meal.

The full objects and advantages of my invention will appear in connection with the detailed description thereof, and the novel features of my inventive idea will be particularly pointed out in the claims.

In the accompanying drawings which illustrate a practical embodiment of my invention, Fig. 1 is an elevational view of the inner face of the rotating burr. Fig. 2 is a view on an enlarged scale taken in section on the line 2—2 of Fig. 1. Fig. 3 is a fragmentary view on an enlarged scale in section on the line 3—3 of Fig. 1 showing the construction of the teeth on the outside burr member. Fig. 4 is a fragmentary view taken in section similar to Fig. 3 but showing the 25 construction of the teeth on the central burr member. Fig. 5 is a fragmentary sectional view taken on a radial line showing one manner of securing the outer burr member to the central member. Fig. 6 is an elevational view on a reduced scale showing the outer 30 scale showing the outer face of the rotating burr. Fig. 7 is an elevational view on the same scale as Fig. 6, and showing the outer face of the stationary burr.

Machines of the character in which my improved burr is employed are well known in the art, it being understood that there are two cooperating burrs, one of which is rotatable and the other of which is stationary with provision for feeding ear-corn 40 through the stationary burr and into the space between the two burrs where the ear-corn is ground into meal which is delivered through a comparatively small space between the burrs at the periphery thereof. Since 45 machines of this general character are well

known in the art, and since the two burrs are alike except for the fact that the stationary burr has an enlarged opening formed in the central portion thereof through which to feed the corn, a detailed description of the construction of one of the burrs will be sufficient to explain the particular features of my invention. In the accompanying drawings, Figs. 1 and 6 illustrate respectively the inner and the outer faces of the rotating burr. 55 As shown, I provide an outside or annular member 10, the inner or working face of which is provided with a multiplicity of radially extending teeth arranged in continuous succession. These teeth are comparatively 60 fine or shallow and are inclined forwardly in the direction of rotation of the burr as will be understood from Fig. 3. The annular member 10 fits around a central member 14 which is dished or convexed outwardly as shown in Fig. 2 and has a central opening 16 through which the shaft of 65 the customary machine passes. The member 14 is secured to the shaft in customary manner and for this purpose is provided with 70 three perforations 18 for receiving bolts commonly used in this connection. The two members 10 and 14 are preferably fitted together by a rabbet joint as shown at 20 and these members may be firmly secured to each 75 other by screws 22 passing through the member 10 and screwed into the member 14 as shown in Fig. 5. The inner face of the member 14 is shown as provided with four ribs 24 occupying a position inclined from a radial position and extending between the outer and inner margins of the member. Alternating with the ribs 24, there are four ribs 26 occupying a position inclined in the 80 opposite direction with relation to the ribs 24 and extending from the outer margins of the member 14 only part way to the inner margin. The inner face of the member 14 is provided with a multiplicity of teeth 28 which are coarser than the teeth 12 of the outer member 10. The teeth 28 are limited 85 to an annular space which starts at the outer margin of the member 14 and extends only part way to the center opening 16, this toothed annular space also stopping short of 90 95 100

the inner ends of the ribs 26. The teeth 28 are formed by cutting a series of grooves ahead of the respective ribs 24 and 26, these grooves being parallel respectively to said ribs in succession and becoming shallower as they proceed outwardly as will be understood from Fig. 5. In order to complete these teeth and provide additional cutting edges, a number of shallow concentric grooves indicated at 30 at the left hand portion of Fig. 1 and also as shown in Fig. 5 are cut across the grooves just referred to. It will be noted by reference to the right hand side of Fig. 1 that an additional set of teeth 32 is provided due to the fact that the two ribs 24 and 26 at this place are spaced further apart from each other than they are for the remainder of the circumference. This additional space provides for entrance of the ends of the ears of corn into the space between the two burrs. As previously stated, the stationary burr is similar to the rotating burr which has been described in detail. Fig. 7 shows the outer face of the stationary burr. As shown in this figure, the central portion of the stationary burr is additionally cut away as indicated at 34 to provide for entrance of the ears of corn. Except for this opening, the same reference characters have been applied to designate the different parts as were employed in connection with the rotating burr. It may be noted, however, that for the stationary burr, the perforations 18 are used in bolting the burr to the frame of the machine in customary manner. In the form shown in Fig. 7, the two members of the burr are secured together by sweating so that the screws 22 are not necessary.

The operations and advantages of my invention will now be obvious. The ears of corn after passing through the opening 34 into the space between the stationary and rotating burrs, are broken up by the action of the ribs which then act to feed the material toward the periphery. The grinding action becomes progressively finer on account of the dishlike shape of the burrs in combination with the decreasing depth of the teeth 28 and the still finer peripheral teeth 12. The latter teeth being inclined forwardly on the rotating burr serve to cut the material to the fineness desired for the meal which is produced.

I claim:

- 55 1. A grinding burr of dishlike form having two sets of spaced ribs on the dished face thereof, said sets alternating with each other and being differently inclined with relation to a radial direction with one of the sets extending further toward the center of the burr than the other set, teeth between the successive ribs occupying an annular space toward the outer ends of the ribs, and a plurality of teeth occupying a concentric outer space.
- 60 2. A grinding burr comprising a central

dished member having two sets of spaced ribs on the dished face thereof, said sets alternating with each other and being differently inclined with relation to a radial direction with one of said sets extending between the outer and inner margins of said member and the other set starting at the outer margin and stopping short of the inner margin, teeth between the successive ribs occupying an annular space toward the outer ends of the ribs, and a separate annular member secured around said central member with its corresponding face provided with a continuous succession of teeth.

3. A grinding burr of dishlike form having two sets of spaced ribs on the dished face thereof, said sets alternating with each other and being differently inclined with relation to a radial direction, two of the adjacent ribs on one side of said burr being spaced further apart than the ribs are for the remainder of the burr, teeth between the successive ribs occupying a space toward the outer ends thereof, and a plurality of teeth occupying a concentric outer space beyond said ribs.

In testimony whereof I hereunto affix my signature.

JOSEPH A. LINDENFELSER.
